(57) CLAIM

The ornamental design for a boot, as shown and described.

DESCRIPTION

FIG. 1 is perspective view of the boot showing the new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The dash-dot-dot broken lines in the figure views indicate features and areas of the boot that form no part of the claimed design. The even length broken lines in the figure views depict stitching, which does form a part of the claimed design.
